UNITED STATES PATENT OFFICE.

ERNEST P. EVERETT, OF NEW YORK, N. Y.

PAPER BARREL.

No. 872,918.

Specification of Letters Patent.

Patented Dec. 3, 1907.

Application filed November 20, 1906. Serial No. 344,244.

To all whom it may concern:

Be it known that I, ERNEST P. EVERETT, a citizen of the United States, and a resident of the city of New York, Astoria, borough of 5 Queens, county of Queens, and State of New York, have invented a new and Improved Paper Barrel, of which the following is a full, clear, and exact description.

This invention is an improvement in paper barrels relating more especially to that class of barrels which are formed by winding a sheet of paper upon itself to form the barrel body. These strips are usually provided with wedge-shaped incisions entering opposite edges in order that when wound the barrel will have the usual oval form. As now placed, these incisions are directly opposite each other, which materially weakens the paper on these lines and often causing it to tear when dampened with an adhesive substance during the winding operation. With my invention this objection is overcome by forming said incisions in opposite edges of the strip in staggered relation. Also provided in connection with the barrel is a novel form of head which is readily applied and removed.

Reference is to be had to the accompanying drawings forming a part of this specification, in which similar characters of reference indicate corresponding parts in all the figures.

Figure 1 is a longitudinal, central section through a barrel embodying my improvement; Fig. 2 is an end view of the same; Fig. 3 is a fragmentary plan of a paper strip which is wound to form the barrel body; Fig. 4 is an edge view of a hoop which is secured in each edge of the barrel, said view showing the hoop when straightened out, 40 and Fig. 5 is an inside view of the same.

In carrying out my invention, I employ a strip of paper or other like material 1, which has cut into its opposite edges a series of wedge-shaped incisions 2, each series of incisions being placed in staggered relation instead of directly opposed as is usual in structures of this character. The incisions are of such length that the center of the strip will be continuous and uncut, whereby it is rendered materially stronger. By this construction, when the strip is wound upon itself to form the barrel body, the paper is not liable to tear across as it would be in constructions wherein the incisions are directly opposed. Especially is this so when the strip is dampened with an adhesive substance

to stick the successive layers together when wound. The blank may be wound by any desired mechanism which will bring the successive layers of the strip close together and 60 press them, forming a closely wound and compact barrel body 3, as illustrated in Figs. 1 and 2. In the winding of this body the edges of the wedge-shaped incisions are brought close together, as shown in Fig. 2, 65 contracting the diameter of the barrel at each end and making it of the usual oval form. The joints formed by these incisions, when the strip is wound, are overlapped by the next adjacent layer, as shown in Fig. 2, 70 in order that the barrel may not be materially weakened on these lines.

The inner layer of the strip forming the barrel body is wound upon hoops 4 arranged upon the inside of the barrel at each end 75 thereof. These hoops, as best shown in Figs. 1, 4 and 5, are formed of sheet metal and are corrugated to provide on their inner faces ribs 5 spaced apart a sufficient distance to receive a head 6. The inner rib 5 of each ring 80 is made continuous whereas the outer rib is cut out in places, making it of an interrupted character.

The barrel heads 6 are each formed preferably of heavy pressed paper or card-board, 85 and constructed with a series of slots or cut-out portions 7 corresponding in number and size to the remaining segments of the interrupted rib 5. By this arrangement each head may be easily passed over an adjacent 90 interrupted rib, and seated on the continuous rib where it is revolved slightly in either direction, bringing it to the position shown in Fig. 2, in which position it cannot be withdrawn. Each continuous rib 5 not only 95 forms a seat for a corresponding head 6, limiting its further inward movement, but also acts to close the slots or cut-out portions 7 in the circumference of the head and prevent the contents of the barrel from wasting out 100 through these openings.

Although I have described the preferred form of construction, I regard the precise embodiment as not material and that the scope of the invention is limited by the annexed 10 claims only.

Having thus described my invention I claim as new and desire to secure by Letters Patent:

1. A barrel having a sheet metal hoop secured in one end thereof, said hoop having corrugations formed therein providing an in-

ner and outer rib spaced apart, the outer rib being interrupted, and a head having cut-out portions in the circumference thereof, adapted to register with said interrupted rib 5 and be passed thereover, for the purpose described.

2. A barrel having a body composed of a strip of paper wound upon itself, a hoop in the barrel near one end thereof covered and 10 secured in place by the inner layer of said strip, said hoop having two ribs spaced apart, one of which is interrupted, and a head hav-

ing cut-out portions in its circumference adapted to register with and be passed over the interrupted rib, for the purpose de- 15 scribed.

In testimony whereof I have signed my name to this specification in the presence of two subscribing witnesses.

ERNEST P. EVERETT.
